UNITED STATES PATENT OFFICE

JOHN M. KERR, OF BAY CITY, MICHIGAN, ASSIGNOR TO BAY CITY SHOVELS, INC., OF BAY CITY, MICHIGAN, A CORPORATION OF MICHIGAN

TENSIONING DEVICE

Application filed October 17, 1929. Serial No. 400,362.

This invention relates to tensioning devices such as used on cranes and excavating machinery in general, and more particularly to a convertible excavator which is convertible from a crane or clam shell to a shovel attachment in which the boom is mounted for rotation as well as a raising and lowering movement.

The prime object of the invention is to design a tensioning device associated with the bucket crowding mechanism, so that when the bucket is loaded and the boom is raised, the device will operate and compensate for the variation in distance between the shaft center on the boom and on which the bucket crowding mechanism is mounted, and the winding drum which is mounted on the excavator platform, and which is caused by the raising and lowering of the boom.

Another object is to design a tensioning device which will permit of a single continuous chain being used, instead of the double chain and the various sprockets and shafts necessary in the conventional construction.

A further object is to provide a very simple, substantial, and rugged device which can be adjusted to suit the take up required, and which can be very readily manufactured and applied.

The above and other objects will appear as the specification progresses, reference being had to the accompanying drawing in which I have shown the preferred embodiment of my invention, and in which like reference numerals indicate like parts throughout the several views thereof.

In the drawing:

Fig. 1 is a fragmentary side view of an excavator provided with a shovel attachment and showing my improved tensioning device in place.

Fig. 2 is a fragmentary side view of the excavating machine with the device shown in position, the dotted lines showing the boom in raised position.

Fig. 3 is a fragmentary top plan view of an excavating machine.

Referring now particularly to the drawing, the numeral 5 indicates the platform of

a full revolving caterpillar type excavator, having the shovel attachment in place, this is provided with the usual boom 6, pivotally connected thereto at the point 7, a shaft 8 being journaled on the boom at a point intermediate its length, and a gear 9 is mounted on the shaft, meshing with a rack 10 provided on the dipper stick, and a sprocket 11 is also mounted on the shaft as shown.

The tensioning device comprises a sprocket 12 mounted on a transversely disposed shaft 13 which is suitably journaled in brackets 14 secured to the face of the platform, said shaft 13 being provided with spaced apart openings in which a pair of vertically disposed bolt members 15 are mounted, the lower end of each bolt being threaded as shown, and nuts 16 and 17 are provided on opposite sides of the shaft for securing said bolts in position.

A similar shaft 18 is spaced from the shaft 13 and is also bored in a like manner to accommodate the bolt members, nuts 19 being threaded on the bolts intermediate their length to limit the downward movement of the shaft 18, similar nuts 20 being threaded on the upper ends of the bolts and coiled springs 21 are interposed between the shaft 18 and the said nut 20, washers 22 and 23 respectively being provided to provide seats for the springs, the shafts 13 and 18 being flattened so that proper bearings are secured for the nuts and washers.

Bearings 24 are provided on the boom in spaced apart relation, and a transversely disposed shaft 25 is journaled therein, links 26 connecting the shafts 18 and 25, and a sprocket 27 is journaled on the shaft 18 as shown, and accommodates the chain as will be hereinafter described.

In practice a sprocket 28 is secured to the winding drum 29 which is mounted on the shaft 30, said shaft being journaled in suitable brackets, (not shown), provided on the excavator platform, and driven from the power plant, (not shown), a continuous chain 31 is trained over the sprocket 28, thence leading around the sprocket 27, thence over the sprocket 11, thence back and

around the sprocket 12, back to the sprocket 28, and it will be obvious that rotation of the drum driven from any suitable source of power, causes rotation of the gear for raising and lowering the bucket and crowding it into the work, and as the boom is raised or lowered, as shown in dotted lines in Fig. 2, the sprocket 27 will be automatically shifted, and compensate for the variation in distance between the shafts 8 and 30.

Under normal operating conditions, the springs 21 are never compressed, but under extreme conditions, when the boom is lowered to the ground, the distance between centers becomes so great that the coil springs will be compressed and permit of a maximum downward travel of the boom.

The position of the boom of course depends on whether it is desired to dig close to the machine, or at a point farther away intermediate the length of the boom, it is also dependent on where the excavated material is dumped, and as the boom is raised or lowered, this mechanism will compensate for the variations in the distance between the shaft centers 8 and 30, so that the chain is always tensioned, eliminating excessive strains and breakage, as well as preventing over-riding of the chain on the sprockets.

From the foregoing description it will be obvious that I have perfected a very simple, substantial, and effective tensioning device for excavating machinery in general.

What I claim is:

1. The combination with an excavating machine, of a tensioning device comprising a transversely disposed shaft journaled on the excavator, vertically disposed members adjustably secured thereto, a second shaft mounted on said members, links pivotally connected thereto and to the excavator boom, and sprockets mounted on said respective shafts.

2. The combination with an excavating machine, of a tensioning device comprising a shaft journaled on the excavator, vertically disposed members secured thereto, a second shaft adjustably mounted on said members and spaced from the first mentioned shaft, sprockets mounted on said shafts, and links connecting said second shaft to the excavator boom.

3. The combination with an excavating machine, of a tensioning device comprising spaced apart transversely disposed shafts, sprockets mounted thereon, vertically disposed members anchored to the lower shaft, means for spacing the upper shaft from the lower shaft, and resilient means interposed between said upper shaft and the end of the members.

4. The combination with an excavating machine, of a tensioning device comprising a transversely disposed shaft, vertically dis-

posed bolts adjustably secured to said shaft, a second shaft mounted on said bolts and spaced from the first mentioned shaft, means for limiting the downward travel of said upper shaft, resilient means interposed between said shaft and the upper ends of the bolts, and a link connecting the upper shaft to the boom of the machine.

5. The combination with an excavating machine, of a tensioning device comprising a transversely disposed shaft, vertically disposed bolts secured thereto, a second shaft mounted on said bolts at a point spaced from the first mentioned shaft, resilient means interposed between said shaft and the upper end of the bolts, sprockets journaled on said transversely disposed shafts, and links for connecting the second shaft to the excavator boom.

6. The combination with an excavating machine, of a tensioning device comprising a transversely disposed shaft, bolts adjustably secured thereto, a second shaft mounted on said bolts and spaced from the first mentioned shaft, means for connecting said shaft to the excavator boom, sprockets on the respective shafts, and means interposed between the upper shaft and the end of the bolts to permit a limited upward movement of said shaft with relation to the lower shaft.

7. In an excavating machine provided with a boom pivotally connected thereto, a tensioning device comprising a lower transversely disposed shaft, bolts secured thereto, an upper shaft spaced from the lower shaft and mounted for movement thereon, resilient means interposed between the upper shaft and the ends of the bolts, links connecting the upper shaft with the boom, and sprockets journaled on the respective shafts.

8. In an excavating machine provided with a boom pivotally secured thereto, a tensioning device comprising a transversely disposed lower shaft mounted on the machine, spaced apart bolts secured thereto, an upper shaft adjustably and slidably mounted on said bolts, resilient means interposed between said shaft and the upper ends of the bolts, sprockets journaled on the respective shafts, and links pivotally connected to the boom and upper shaft respectively.

In testimony whereof I hereunto affix my signature.

JOHN M. KERR.
